TURBINE LOCOMOTIVE

Filed Dec. 4, 1925

UNITED STATES PATENT OFFICE.

HEINRICH HERRMANN, OF ESSEN, GERMANY, ASSIGNOR TO FRIED. KRUPP AKTIEN-
GESELLSCHAFT, OF ESSEN-ON-THE-RUHR, GERMANY.

TURBINE LOCOMOTIVE.

Application filed December 4, 1925, Serial No. 73,244, and in Germany December 31, 1924.

This invention relates to turbine locomotives which are driven by high-pressure steam. If such turbines are to possess a good thermodynamic efficiency, they must be 5 made multistage. Besides, even in case of high outputs and consequent large steam quantities, the cross-sections of the distributors in the high-pressure stages of the high-pressure turbines become extraordinarily 10 small because of the very small specific volume of the high-pressure steam, so that already in these cases difficulties are encountered in the manufacture of the distributors. In view of the considerable saving 15 of steam and fuel, the expensive multistage construction is used for the main driving turbines of turbine locomotives driven by high pressure steam in spite of the difficulty of manufacturing the distributors for the 20 high pressure stages. But, circumstances are different with regard to the auxiliary turbines used for operating the several pumps for water of condensation, the furnace blower and the re-cooling plant. These 25 are small engines the output of each of which amounts from about 1/25 to 1/15 at most of the output of the main turbines. In addition to the particularly sensible general difficulties in the manufacture of such small 30 units as high-pressure turbines, such as the difficult manufacture of the distributors and the great length of structure owing to the multistageness, there is still entailed the essential drawback of the long high-pressure 35 pipes, which must eventually be provided even with flexible pipe-joints, and of the constantly operative control valves which are difficult to keep tight.

According to the invention, these difficulties are overcome in a simple manner by driving only the main turbines with high-pressure steam, while the auxiliary turbines are driven by steam of a lower pressure.

The accompanying drawing is a diagrammatic view of an embodiment of the subject matter of the invention.

The power plant comprises a high-pressure boiler A from which a steam pipe a^1 extends to the engine serving to drive the

locomotive and consisting of a high-pressure turbine B^1 and a low-pressure turbine B^2 connected with the former by a pipe b^3 . The exhaust-steam side of the turbine B^2 is connected by a pipe b^4 with a condenser C. Another boiler D designed to generate steam 55 of a pressure lower than that in the high-pressure boiler A, is connected by a steam pipe d^1 with the inlet opening of each of two turbines E and F designed to drive auxiliary engines such as, for instance, a pump 60 for water of condensation and a furnace blower. The exhaust steam of the auxiliary turbines E and F is fed through pipes k^1 and m^1 to two heaters K and M through which passes a pipe c^1 leading from the condenser 65 C to the boiler A and designed to heat the water of condensation returning to the boiler A. The water of condensation formed in the heaters K and M is forced by a feed pump N through a pipe n^1 directly into the 70 low pressure boiler D, so that there is produced for the low pressure boiler an entirely separate circulation from the boiler D through the auxiliary turbines E, F, the heaters K, M and the feed pump N back to 75 the boiler D. The low pressure boiler D has disposed in it as a heating element a coiled tube P to which steam from the high-pressure boiler A is supplied through a pipe p^1 . The exhaust steam end of the coiled 80 tube P is connected by a pipe p^2 with the condenser C. The water of condensation formed in the coiled tube P is collected in a steam separator Q which prevents the water of condensation from flowing into the 85 condenser. A pump G is inserted in the pipe c^1 for water of condensation. The boiler D has, besides, connected to it a pipe d^2 through which steam from the boiler D may be supplied for train heating purposes. 90

In view of the foregoing description it does not seem necessary to give further explanations regarding the operation of the plant.

Claim:

95 In a power plant, the combination of main driving turbines and auxiliary turbines, a high-pressure boiler for generating

the steam required for driving the main turbines, a low-pressure boiler for generating the steam required for driving the auxiliary turbines, feed water heaters for the high-pressure boiler connected with the auxiliary turbines and designed to condense the exhaust steam of the auxiliary turbines, and

means for returning the water of said condensation into the low-pressure boiler.

The foregoing specification signed at 10 Cologne, Germany, this 30th day of October, 1925.

HEINRICH HERRMANN.
